AIR CHECK DOOR CLOSER

Herbert A. Simpson, Ionia, Mich.

Application July 5, 1947, Serial No. 759,061

4 Claims. (Cl. 16—66)

1

This invention relates to air check door closers, and more particularly to a door closer of the type having a coil spring for urging a door to closed position, and connected to the door by telescoping means designed to utilize a cushion of air to prevent slamming of the door.

One object of this invention is to provide a door closer of the above nature having means to approximately equalize the effect of the spring force regardless of the degree of extension of the spring.

Another object is to provide a device of the above nature which includes a stop to limit opening movement of the door.

Another object is to provide a device of the above nature which will have the dependability and other characteristics of the more expensive hydraulic door checking devices, without the disadvantages attendant upon the use of a liquid.

A further object is to provide a device of the above nature in which the air cushion serves to actuate a brake which provides the greater part of the checking force, the air cushion being compressed only enough to actuate the brake.

Still another object is to provide a device of the above nature having a bracket which is readily adaptable to mount the door closer at either the inner or the outer side of the door, and also adaptable for use with doors having either a right-hand or a left-hand swing.

A further object is to provide a door closer of the above nature which will be simple in construction, inexpensive to manufacture, easy to install and manipulate, compact, ornamental in appearance, and very efficient and durable in use.

With these and other objects in view, there have been illustrated on the accompanying drawing, two forms in which the invention may conveniently be embodied in practice.

In the drawing,

Fig. 1 is a plan view of a door closer showing how it is attached to a door and a door jamb.

Fig. 2 is a side elevation of the same.

Fig. 3 is a cross-sectional view on the line 3—3 of Fig. 2, showing the spring housing.

Fig. 4 is a cross-sectional view, on a larger scale, taken along the line 4—4 of Fig. 5, and showing details of the spring mechanism.

Fig. 5 is a cross-sectional view on the line 5—5 of Fig. 4, with the parts in the position they assume when the door is closed.

2

Fig. 6 is a cross-sectional view similar to Fig. 5, showing the parts in the position they assume when the door is open.

Fig. 7 is a fragmentary longitudinal sectional view on a larger scale of the brake cylinder and one form of brake mechanism.

Fig. 8 is a fragmentary longitudinal sectional view of the brake cylinder, and a second form of brake mechanism employing a pair of pivoted brake shoes.

Fig. 9 is a cross-sectional view taken on the line 9—9 of Fig. 8.

Fig. 10 is a longitudinal sectional view similar to Fig. 8, but rotated 90 degrees therefrom, with the brake shoes in inactive positions.

Fig. 11 is a longitudinal sectional view of the same, similar to Fig. 10, showing the brake shoes in braking positions.

Fig. 12 is a longitudinal sectional view of the brake cylinder, showing a third form of compression cup mounting, with the compression cup in its inactive condition.

Fig. 13 is a longitudinal sectional view similar to Fig. 12, showing the compression cup in the shape it assumes under pressure.

Referring now to the drawings in which like reference characters denote corresponding parts throughout the several views, the letters C, D, and J indicate a door closer, a swingable door, and a door jamb, respectively.

The door closer C is provided with a Z-shaped mounting bracket 10 including parallel offset portions 11, 12 for supporting a substantially cubical spring housing 13—screws 14 and 15 being provided for securing the bracket 10 to the jamb J and the housing 13, respectively. The housing 13 has an end wall 16, a front wall 17, a back wall 18, a top wall 19, and a bottom wall 20. The end wall 16 is provided with an outside reinforcing plate 21 tapped for receiving the mounting screw 15, and the back wall 18 is provided with an identical tapped reinforcing plate 22, for a purpose to be described hereinafter.

Adjacent to the front wall 17 and opposite the end wall 16, the housing 13 is provided with a vertical reinforcing flange 23, which, together with a swingable bracket 24, is adapted to close the remaining sixth side of the cubical housing 13. The bracket 24 includes inwardly-extending horizontal top and bottom flanges 25, 26, apertured

to receive a vertical pivot pin 27, mounted in the rear corners of the top and bottom walls 19, 20.

In order to limit the swinging movement of the bracket 24, the back wall 18 terminates at a distance from the pivot pin 27, forming a stop abutment 28.

The bracket 24 is operatively connected with the door D by a telescoping guide housing, generally indicated by 29, having one end rigidly mounted upon one face of the bracket 24, its other end being connected to the door D by a bracket 30 and screws 31. The telescoping housing 29 will be described in more detail hereinafter.

The spring housing 13 contains a coil spring 32 having an upper inwardly-bent end 33 received in a recess 34 of a spring base block 35. The block 35 is mounted upon a square shaft 36, held in central apertures 37, 38 in the top and bottom housing walls 19, 20, respectively. The shaft 36 carries a toothed ratchet disk 39 exteriorly of the housing for adjustable securement by a pivoted pawl 40, whereby one end of the spring 32 may be selectively fixed against rotation, in several positions.

The spring 32 also has a lower outstanding end 41 confined in an aperture 42 in a vertical connecting plate 43 of a U-shaped yoke 44 located within the spring housing 13. The yoke 44 has upper and lower horizontal apertured plates 45, 46 which embrace the spring 32 and the spring base block 35, and receive the square shaft 36 rotatably in the apertures thereof. It will thus be seen that the U-shaped yoke 44 may be rotated against the force of the spring 32.

In order to connect the swingable bracket 24 operatively to the U-shaped yoke 44, provision is made of a bent link 47 (Fig. 5), pivotally secured at one end to an anchor pin 48 held in apertures in the bracket flanges 25, 26, and secured at the other end in an aperture 48a in the vertical plate 43 of the U-shaped yoke 44.

The telescoping housing 29 includes an inner sliding guide tube 49 threaded upon a mounting disk 50 fixed upon the outer face of the swingable bracket 24. An outer cylinder 51 of the housing 29 telescopes over the inner tube 49 at one end, and is provided with a domed cap 52 at its other end, said cap being pivotally joined to the connecting bracket 30, as by a pin 53.

The action of the spring 32 in closing the door is checked by mechanism which includes a piston rod 54 threaded into the mounting disk 50 by a reduced end 55, and extending concentrically within the inner guide tube 49, and the outer cylinder 51.

Brake mechanism

Referring now to Fig. 7, the piston rod 54 is provided with an extension 56 which includes an integral sleeve portion 57 slidably embracing the end of the rod 54. The rod extension 56 is retained for limited sliding movement upon the rod 54 by a pair of diametrically opposed slots 58 in the sleeve portion 57, which receive a cross pin 59 fixed in the rod 54.

The ends of the cross pin 59 support a tubular portion 60 of a rigid backing washer 61 in fixed position relative to the rod 54 and exteriorly of the extension 56. The washer 61 serves as an abutment for a flexible brake cup 62 of a diameter to fit within the cylinder 51. A nut 63 threaded upon the outer end of the extension 56 holds thereon a retaining rigid washer 64, a flexible compression cup 65 preferably of leather and a rigid expander cone 66 having a frusto-

conical peripheral surface 67. A restoring coil spring 68 is disposed upon the extension 56 and normally holds the expander cone 66 and the brake cup 62 in substantially disengaged relation.

5 A headed screw 69 is loosely threaded in the end cap 52 to serve as an adjustable bleed valve, whereby the speed of operation of the door closer will be governed.

Operation

10 In the operation of the door closer, opening movement of the door D, by means of the telescoping means 29, will swing the bracket 24 from the position shown in Fig. 5 to the position shown in Fig. 6, against the force of the spring 32.

15 The toothed disk 39 and the pawl 40 will first have been adjusted to tension the spring 32 to produce a desired closing force. As the yoke 44 is swung, the spring 32 will undergo a "build-up," or increase in tension. It will be noted, however,

20 that the effective radius at which the link 47 applies its force to the yoke 44 will increase as the yoke is swung, whereby the spring "build-up" will be approximately compensated for and substantially the same closing force will be exerted

25 upon the door at all positions thereof.

The force of the spring 32 will be transferred to the door through the lever action of the tube 49 and the cylinder 51 telescoping thereon, thereby relieving the piston rod 54 and check mechanism of any side thrust.

When the door starts to close, the piston rod 54 will move inwardly in the cylinder 51 (to the right in Fig. 7), and as soon as air pressure is picked up by the flexible compression cup 65, the

35 rod extension 56, with the expander cone 66 thereon, will be retarded against the force of the spring 68, thereby pressing the frusto-conical surface 67 of said cone into the brake cup 62. The cup 62, being flexible, will be expanded by the cone

40 not only at its edge, but also at the root of its cylindrical portion, due to a tendency of said cup to flatten under pressure. Accordingly, the air pressure against the compression cup 65 will cause the cup 62 to act as a frictional brake against the cylinder wall, and only a minor and incidental part of the direct checking force will be provided by said air pressure.

The bleed valve 69 will serve, as in the more conventional air check door closures, to control 50 the speed at which the air is released, and hence the speed of the closing movement.

Second form

In the second form of the invention, shown in 55 Figs. 8, 9, 10, and 11, provision is made of an outer cylinder 70 and a piston rod 71 mounted in all respects as the cylinder 51 and piston rod 54 of the first form. The piston rod 71 is provided with an extension 72 comprising a sleeve

60 portion 73 slidable on the rod 71, and a threaded stud 74 fixed in one end of the sleeve portion 73.

The extension 72 is secured for limited sliding movement on the rod 71 by a pair of slots 75 in the sides of the sleeve portion 73 which receive 65 projecting end portions of a cross pin 76 fixed in the piston rod 71. The ends of the cross pin 76 are provided with heads 77 which retain the legs of a pair of U-shaped cam members 78 upon the cross pin 76 at each exterior side of the sleeve

70 portion 73—said cross pin being received in slots 78a extending inwardly from the ends of the legs of said U-shaped cam members 78. The slots 78a are so proportioned that when the parts are in inactive position, as in Fig. 10, the cross pin 76 75 will engage the inner ends of said slots 78a.

The outer curved parts of the U-shaped cam members 78 are engaged at one edge by a pair of fulcrum hooks 79, each formed centrally on the inside of one of a pair of semi-cylindrical brake shoes 80. The brake shoes are further provided with frictional facings 81 upon their outer surfaces, and have inwardly turned ears 81a at their forward edges.

The stud 74 of the rod extension 72 is provided with a nut 82 threaded thereon for coaction with a shoulder 83 of the rod extension 72 to hold a flexible compression cup 83a having a retaining washer 84 and a backing washer 85.

As a means for holding the rod extension 72 and compression cup 83a normally in their most extended position, a restoring coil spring 86 is provided upon the extension 72. The spring 86 bears at one end against the rigid backing washer 85, and at the other end against the U-shaped cam members 78 through the medium of a bearing ring 87.

The modified form of the device shown in Figs. 8, 9, 10 and 11 will operate generally in the same manner as described above, except that the cam-actuated brake shoes perform the braking function. In this device, when the compression cup 83a picks up air pressure, said cup 83a, acting through the ears 81a, will press the brake shoes 80 rearwardly with relation to the cross pin 76 whereby the U-shaped cam members 78 will be tilted as shown in Fig. 11. Inasmuch as the cross pin 76 engages the inner ends of the slots 78a, the cam members 78 will have an effectively greater radius when tilted and will press the brake shoes 80 outwardly into frictional braking engagement with the cylinder surface.

Third form

The third form of the invention shown in Figs. 12 and 13 includes generally the same structure as was disclosed in the first form, shown in Figs. 1 to 7, but is distinguished therefrom by an improved specific mounting for the compression cup.

In this form, a flexible compression cup 88 is mounted upon the end of a rod extension 89 for sliding movement within an outer cylinder 90. A backing for the cup 88 is provided by a rigid expander cone 91 having a rearwardly-extending frusto-conical surface 92 and a front surface including a frusto-conical portion 93 surrounding a flat apertured transverse central portion 94, received upon the rod extension 89. A nut 95 and a washer 96 serve to hold the cup 88 in its assembled relation against the flat central portion 94 of the cone 91.

It will be understood that the rod extension 89, and the expander cone 91 are the counterparts of the extension 56 and the cone 66 as shown in Fig. 7. A restoring spring 97 performs the same function as the restoring spring 68 in the first form.

In the operation of the third form of the invention shown in Figs. 12 and 13, a frusto-conical front portion 93 of the expander cone 91 permits the compression cup 88 to flex rearwardly under the influence of pressure in the cylinder 90, thereby assuming the shape shown in Fig. 13.

The purpose of this feature is to provide repeated flexing of the cup 88 with each movement of the door closer, thereby preventing the cup material from taking a "set" and thus failing to pick up compression. This construction also prevents excessive friction or vacuum drag, such as

sometimes occurred in prior door closures during the return stroke of the piston.

Further, the mounting bracket 10 is equally well adapted to provide either right or left-hand mountings merely by rotating the door closer 180 degrees with relation to said bracket, said rotation being permitted by the releasable clamping screw 15 secured in the reinforcing plate 21 or 22, as the case may be. Thus, the bracket 10, when inserted from the position shown in Fig. 2, will be adapted for mounting the door closer in reversed position upon the opposite door jamb.

While the improved door closer has been herein described as applied in an inside mounting, it may, if desired, also be applied to a door closer in an outside mounting. In this case the Z-shaped mounting bracket will be applied to the upper rail of the door, and the offset bracket portion 12 will be secured by the screw 15 to the back reinforcing plate 22, the connecting bracket 30 being secured to the door lintel.

One advantage of the three forms of door closers herein disclosed is that only a small degree of air pressure is required to operate the check means. The air compression cup is never called upon to resist excessive pressure, and consequently will have a long life and will not require constant adjustment.

Further, the closer not only has the dependability and smoothness of operation found in hydraulic door closers, but will also maintain uniform operation despite changes of temperature.

The form of the invention shown in Figs. 8, 9, 10, and 11 has been found particularly suitable for heavy doors because of its large braking surface.

The brake mechanisms herein disclosed are claimed in my copending divisional application Serial Number 64,851, filed December 11, 1948, entitled Check mechanism for door closers.

While there have been disclosed in this specification three forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a door closer, a coil spring, means securing one end of said spring in fixed position, a rotatable yoke embracing said spring and securing the other end thereof, swingable means adapted for connection to a door and mounted upon a fixed pivot adjacent said yoke, and a link connected at one end to said swingable means and at its other end to an outer edge of said yoke, whereby the spring is adapted to exert a force through said yoke, link, and swingable means to close the door.
2. In a door closer, a mounting means including a housing open on one side, a shaft adjustably secured in opposite walls of said housing, a coil spring secured at one end thereof to said shaft, a yoke rotatably mounted on the shaft within said housing and embracing said spring, said spring being secured at its other end to said yoke, swingable means adapted for connection to a door and including a bracket portion adapted to close the open side of the housing and pivoted therein, and a link connected at one end to said bracket

portion and at its other end to an edge of said yoke.

3. The invention defined in claim 2, wherein the bracket portion in its closed position lies contiguous to the yoke, and the link extends past said shaft, whereby the effective radius of the force applied to the yoke by the link will increase as the bracket portion is moved to open position.

4. In a door closer, a swingable means adapted for connection to a door to urge the door to closed position, and means for mounting said swingable means including a housing, a spring therein connected to said swingable means, a tapped reinforcing plate secured to one side of said housing, a second tapped reinforcing plate secured to the rear of said housing, a bracket, and a screw whereby said plates may be selectively attached to said bracket in erect and inverted position, for inside, outside, left-hand and right-hand mounting of the door closer.

HERBERT A. SIMPSON.
